CLAIM

U.S. PATENT DOCUMENTS

The ornamental design for a radio frequency identification tag antenna assembly, as shown and described.

DESCRIPTION

The present application may also be considered to be related to co-pending U.S. Design patent application Ser. No. 29/220, 504 filed Dec. 30, 2004, in the name of inventor Ronald A. Oliver, entitled “Radio Frequency Identification Tag Antenna Assembly”, commonly owned herewith.

The present application may also be considered to be related to co-pending U.S. Design patent application Ser. No. 29/220, 496 filed Dec. 30, 2004, in the name of inventor Ronald A. Oliver, entitled “Radio Frequency Identification Tag Antenna Assembly”, commonly owned herewith.

The FIGURE is a top plan view of a radio frequency identification tag antenna assembly showing my new design.
